UNITED STATES PATENT OFFICE.

AUGUST HILDT, OF NEW YORK, N. Y., ASSIGNOR TO LOUIS DRYFOOS & CO.,
OF SAME PLACE.

DESIGN FOR THE ORNAMENTATION OF SKIRTS, LININGS, &c.

SPECIFICATION forming part of Design No. 17,812, dated October 25, 1887.

Application filed September 5, 1887. Serial No. 218,909. Term of patent 7 years.

To all whom it may concern:

Be it known that I, AUGUST HILDT, a citizen of the United States, and a resident of the city, county, and State of New York, have invented a new and original Design for Surface Ornamentation of Skirts, Linings, and other Similar Articles, of which the following is a specification.

My design is for the surface ornamentation of skirts, linings, quiltings, and similar articles; and it consists of the parallel rows of tangent semicircles and the intervening rows of rectangular figures arranged and disposed all as will hereinafter more fully appear.

In the accompanying drawing I have represented in a single figure a portion (containing all the elements) of my design as it appears when applied upon the article or goods, dotted lines being employed to indicate stitches, and these lines arranged or grouped in accordance with my design, this illustration being deemed sufficient for purposes of this specification.

For convenience of description the various parts of the design may be referred to as follows:

A A A are semicircles located one above the other, or in parallel rows, of any number, touching each other and turned in the same direction.

B B B are semicircles similar to the semicircles A A A, and tangent to them and turned in the opposite direction, the two series forming a vertical row of tangent semicircles.

C C C are figures similar to the figures A A A, and D D D figures similar to B B B, the distance between the centers of the figures B and C being equal to twice the length of the radii of either. The ones B and C are joined by

straight lines of stitching, as *a b c d*, and the lines *a b c d* cross each other, as plainly shown, affording between the vertical rows of semicircles vertical rows of rectangular figures. These rectangles will be varied in size by vary-

ing the size of the semicircles. The remaining curves are joined in like manner.

The description so far indicates the general principles upon which the lines and semicircles are grouped. To increase the number of lines and semicircles in any given space the same general arrangement is followed for the groundwork, and upon this or to this is added another series of lines and curves precisely like the first, as indicated at the lower part of the figure, wherein, for instance, a semicircle, as A', is struck from a center located at the point where two curves A A touch each other. The cross-lines between all the curves drawn, as before explained, form a series of small rectangles, as will be readily seen, and these fill the space between the vertical rows of semicircles.

The groundwork alone may constitute the whole design in any pattern, or the duplicate thereof may be employed entirely. I prefer to employ both together, the lower part forming a heavy margin for the pattern, while the upper part appears lighter; but the upper and lower parts might be reversed.

This design is to be distinguished from one in which the semicircles are arranged so that the straight lines joining their extremities do not cross each other at right angles, but form parallelograms or lozenge-shaped figures.

Having now fully described my design, what I claim as new, and desire to secure by Letters Patent, is—

In a design for the ornamentation of skirts, &c., the parallel rows of tangent semicircles and the intervening rectangular figures, substantially as described.

In testimony whereof I have hereunto set my hand.

AUGUST HILDT.
